(57) **CLAIM**

The ornamental design for a display screen with animated graphical user interface, as shown and described.

DESCRIPTION

FIG. 1 is a front view of a display screen with animated graphical user interface, showing a first image of a first embodiment of the new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a front view of a display screen with animated graphical user interface, showing a first image of a second embodiment of the new design;

FIG. 11 is a second image thereof;

FIG. 12 is a third image thereof;

FIG. 13 is a fourth image thereof;

FIG. 14 is a fifth image thereof;

FIG. 15 is a sixth image thereof;

FIG. 16 is a seventh image thereof;

FIG. 17 is an eighth image thereof; and,

FIG. 18 is a ninth image thereof.

The appearance of the transitional image sequentially transitions between the images shown in FIGS. 1-9 and FIGS. 10-18. The process or period in which one image transitions to another image forms no part of the claimed design.

The broken line showing of the display screen and graphical user interface are included for the purpose of illustrating environmental structure and portions of the article and form no part of the claimed design.
